UNITED STATES PATENT OFFICE.

EUGENE N. STROM, OF CHICAGO, ILLINOIS, ASSIGNOR TO PETTIBONE MULLIKEN COMPANY, OF CHICAGO, ILLINOIS, A CORPORATION OF ILLINOIS.

RAILWAY-CROSSING.

1,140,008.

Specification of Letters Patent.

Patented May 18, 1915.

Application filed February 3, 1915. Serial No. 5,885.

To all whom it may concern:

Be it known that I, EUGENE N. STROM, a citizen of the United States, residing at Chicago, in the county of Cook and State 5 of Illinois, have invented a new and useful Improvement in Railway-Crossings, of which the following is a specification.

My invention relates to an improvement in railway-crossings, the intersecting sections 10 of which are cast of hard metal, more usually manganese steel. The pounding of the wheels to which this cast-section of a railway-crossing is subjected at the intersection of the grooves for the wheel-flanges, tends to 15 fracture it at that point; and when thus fractured the entire section has to be replaced by a new one. The impact of the wheels, moreover, sometimes extends the fracture beyond that point into the body of 20 the casting.

The object of my invention is to avoid this necessity, by providing the center of the section as a removable and replaceable hard-metal insert containing the intersecting 25 grooves; and, furthermore, to so support the insert that the blows of the wheels against it will not be transmitted to the remainder of the section, thereby to avoid also fracturing the latter, to which there would 30 otherwise be a tendency.

In the accompanying drawing, Figure 1 shows, by a plan view, a hard-metal crossing-intersection provided with my improvement, and Fig. 2 is an enlarged section on 35 line 2, Fig. 1, but omitting the ties.

The crossing-section 3, provided with the usual wheel-flange grooves, is a casting of manganese steel. In the center of this casting is formed an oblong generally rectangular hole 4 tapering upwardly. In this hole fits a similarly shaped insert 5, which is 40 preferably a casting and also of manganese steel, containing the intersecting wheel-flange grooves, as shown. This insert, which 45 fits wedge-like in the hole 4 against displacement or withdrawal therefrom in the upward direction, is adapted to be so supported as to prevent the blows of the wheels against it from being transmitted to the 50 remainder of the section 3, so as to shield the latter against fracture by such transmission. As the preferred means for thus supporting the insert, it is provided with an expanded

base 6, preferably cast integrally with it. The insert seats at the base 6 on the ties 7, 55 whereby the blows referred to are not only cushioned, thereby reducing this tendency to fracture the insert at the intersecting grooves therein, but also preventing transmission of the impacts to the remainder of 60 the section 3, and thereby removing all tendency to fracture of the latter.

While I have herein, for the sake of brevity, shown and described my improvement in its application to a railway-crossing, 65 its advantages are equally great, and the improvement is the same, when applied to a hard-metal railway-frog. I therefore desire to be understood as intending the expression "crossing" employed in the claims to include a frog as an equivalent structure embodying my invention.

What I claim as new and desire to secure by Letters Patent is:—

1. A cast hard-metal crossing-section provided with an opening extending through it at the crossing point, and a hard-metal insert fitting and confined in said opening, 75 said section and insert containing grooves for the flanges of wheels traversing the 80 crossing, and said insert being supported to take the wheel-blows at the intersecting grooves therein and shield the remainder of said section against transmission thereto of 85 said blows.

2. A cast hard-metal crossing-section provided with an opening extending through it at the crossing point, and a hard-metal insert fitting and confined in said opening and provided with an expanded seating base extending underneath said section, said insert and section containing grooves for the flanges of wheels traversing the crossing. 90

3. A cast hard-metal crossing-section provided with an upwardly tapering opening 95 extending through it at the crossing point, and a hard-metal insert fitting and confined in said opening and provided with an expanded seating base extending underneath said section, said insert and section containing grooves for the flanges of wheels traversing the crossing. 100

EUGENE N. STROM.
